UNITED STATES PATENT OFFICE.

JULIUS STEPHANSEN, OF DRAMMEN, NORWAY.

DEWATERING APPARATUS FOR PULP.

Application filed May 4, 1926, Serial No. 106,704, and in Norway April 4, 1925.

It is known to take up pulp on an endless sieve by means of suction boxes or rotating suction drums. It is also known to construct large screening cylinders covered with a stationary screen, the different parts of which are alternately and at certain portions of the circumference subjected to suction, partly in order to increase the output of the machine and partly in order to exercise such suction upon the deposited pulp layer that the same is freed from water.

These apparatus are complicated and costly, and moreover it has been difficult to obtain, by means thereof, a sufficiently strong cylinder, which may stand the relatively great stress to which the peripheric portions thereof are subjected by contacting pressure drums &c.

Drums are also known which are intended to be used at great pressures and which possess deep slots or grooves which extend around the periphery of the drum and receive the water which is filtered through the screen. The said water is then removed from the slots by means of a suction box arranged at the free end of the outer surface of the slot drums. This arrangement is objectionable in that the point of the drum periphery which is nearest to the externally arranged suction box is subjected to the most intensive suction action, which latter, of course, decreases with the distance from the suction box, as the suction only can propagate circumferentially through the narrow slots, which in the neighbourhood of the section box become full of water. This is objectionable, as the suction action rather should increase than decrease as the thickness of the mass layer increases, which it does as distance of the said layer from the suction box is increasing.

The object of the present invention is to provide a dewatering apparatus by means of which the above named drawbacks are avoided. The invention resides essentially therein that the apparatus is so constructed that an even suction action is obtained at the entire effective surface thereof.

The annexed drawing shows in section by way of example one embodiment of a dewatering apparatus according to the invention.

In the drawing 1 is the hollow suction drum, the interior of which is placed under a vacuum. The periphery of the drum is provided with apertures 7 which may be circular, as in an usual perforated plate, or oblong, as in a strainer plate, which apertures extend into the inside of the drum. An endless felt or strainer sieve 6 passes around the drum in a manner known per se. At those portions where the said felt or sieve does not cover the drum there is arranged a cap or cover plate 5, which lies closely to the cylinder, in such manner that no air can at that place enter into the interior of the drum through the perforations.

The action of the apparatus is as follows:

The felt or sieve 6 moves past the open back water channel 2 and receives a thin deposit of pulp. The back water is collected and may be utilized for diluting purposes or the like. As the felt 6 moves along with the rotating drum 1 the vacuum in the drum exerts a suction action upon the pulp upon the felt. The water hereby drawn off passes through the felt 6 and the apertures 7 in the periphery of the drum 1, into the inside thereof, from where the water is removed through the hollow stub shaft 3 or through openings 4 in the end wall of the drum, which openings are connected with a suitable vacuum pump (not shown). The deposited pulp layer passes then in the usual manner past pressure drums 8 and is at last removed from the felt in known manner.

Having now particularly described and ascertained the nature of my said invention and in what manner the same is to be performed, I declare that what I claim is:

1. In a pulp dewatering apparatus, the combination of a pulp container, a rotatable perforated drum forming one side wall of said container, an endless felt or sieve passing through said container and partly around said drum, and means associated with said

drum to prevent passage of fluids through said perforations along that part of the periphery of the drum not in contact with said felt.

5 2. In a pulp dewatering apparatus, the combination of a pulp container, a rotatable perforated drum forming one side wall of said container, an endless felt or sieve passing through said container and partly

around said drum, and means associated with said drum to prevent access into the interior thereof along that part of the periphery of the drum not in contact with said felt, said means comprising an arcuate cap disposed about the outside of and closely fitting the periphery of said drum.

In testimony whereof I affix my signature.
JULIUS STEPHANSEN.
